(57) **CLAIM**

The ornamental design for a sauna stove tent as shown and described.

DESCRIPTION

FIG. 1 is a perspective view of a new design for a sauna stove tent;

FIG. 2 is a front view of the sauna stove tent shown in FIG. 1;

FIG. 3 is a rear view of the sauna stove tent shown in FIG. 1;

FIG. 4 is a right side view of the sauna stove tent shown in FIG. 1;

FIG. 5 is a left side view of the sauna stove tent shown in FIG. 1; and,

FIG. 6 is a top view of the sauna stove tent shown in FIG. 1.

The bottom view of the sauna stove tent shown in FIG. 1 is not visible during use.

The broken lines shown in the drawings are for the purpose of illustrating portions of the sauna stove tent and form no part of the claimed design. Any surface shading is used solely to show the character or contour of the surface represented.

1 Claim, 6 Drawing Sheets
